UNITED STATES PATENT OFFICE.

EDWARD BURKE, OF PHILADELPHIA, PENNSYLVANIA, ASSIGNEE TO UNION SPECIAL
MACHINE COMPANY, A CORPORATION OF ILLINOIS.

FOLDING AND GUIDING DEVICE FOR SEWING-MACHINES.

1,119,240.

Specification of Letters Patent.

Patented Dec. 1, 1914.

Application filed November 21, 1903. Serial No. 886,435.

To all whom it may concern:

Be it known that I, EDWARD BURKE, a citizen of the United States, residing at Philadelphia, in the county of Philadelphia, State of Pennsylvania, have invented certain new and useful Improvements in Folding and Guiding Devices for Sewing-Machines, of which the following is a description, reference being had to the accompanying drawing and to the letters and figures of reference marked thereon.

This invention relates to sewing machines and is designed particularly as an improvement upon the ruffling sewing machine for which U. S. Letters Patent were granted to Russel G. Woodward, on July 31, 1900, No. 655,143.

The principal object of the invention is to provide a folding guide by means of which a double hem or pocket may be formed at the edge of one piece of fabric, while a second piece is ruffled and inserted therein.

A further object of the invention is to provide an improved sectional folding guide which may be opened to facilitate the introduction of the fabric.

A still further object of the invention is to provide a folding guide which will insure the guiding of the ruffle strip into proper position within the pocket and maintain its inner edge in a plane between the two needles of the machine.

The invention consists in the novel construction and arrangement of parts herein-after described and referred to in the appended claims.

In the accompanying drawings, which illustrate the invention, Figure 1 is a side elevation of a sewing machine showing a folding guide constructed in accordance with the invention. Fig. 2 is a transverse sectional view, of the parts above the cloth plate, on the line 2-2 of Fig. 1. Fig. 3 is a plan view of the folding guide in position. Fig. 4 is a detail perspective view of the guide detached. Figs. 5, 6 and 7 are detail sectional views of the guide, on the lines 5-5, 6-6, and 7-7 of Fig. 3. Fig. 8 is a sectional perspective view, on an exaggerated scale of the product of the machine.

Similar numerals of reference are employed to indicate corresponding parts throughout the several figures of the drawings.

The construction of the machine proper is similar to that of the well known two line Union Special machine, with the parts arranged and constructed as shown in the Letters Patent hereinbefore referred to and to which reference is made for details not specifically referred to in this specification.

The main shaft 1 operates in the usual manner to transmit movement to the frame 23, which carries the ruffling blade 25, the working edge of the latter being so arranged, however, that it does not extend across the plane of both needles, but is designed to feed the ruffling strip so that the innermost stitching mechanism alone will act thereon. At the front of the cloth plate is secured a plate 10 which carries a folding guide formed, in the present instance, in sections 11 and 12, the section 12 being movable relatively to the section 11, so that the guide may be opened to facilitate the introduction of the fabric. The movable section 12 is mounted, in the present instance, on a slide plate 15, the edges of which are adapted to guides 16 carried by the plate 10, and said plate 15 is connected to a pivotally mounted operating lever 17 by means of a link 18. The lever is preferably provided with a handle arranged within convenient reach of the operator, and while the handle and plate 15 are shown above the carrying plate, they may be readily arranged below the same if found desirable. It will thus be seen that I have provided a guide with a movable section which may be withdrawn from the stationary section for the insertion of the fabric. It will be noted that the edges of the stationary and the movable sections of the guide, when in closed position, as shown in Figs. 5, 6 and 7, are in contact, and that these edges, therefore, serve as stops to suitably space the sections of the guide, so that a proper guiding space may be formed for the fabric.

Before proceeding further with the description of the mechanism reference is had to Fig. 8 which shows the product of the machine, and from an examination of this operation of the folding guide will be better understood. The main fabric *a*, being part of a skirt or other article, is folded at *b*, and the fabric is thence folded again at *c* and again at *d*, the last fold being to turn in the raw edge. This forms what

may be termed for convenience, a double hem between *b* and *d* and in the pocket or space between these is fed the ruffle strip *e*, which, however, does not extend to the bottom of the pocket. The fabric is stitched, there being two distinct lines of stitching *f* and *g*, the stitches *f* passing through the fabric *a* alone, while the stitches *g* pass through both fabrics, bending down the double hem and securing the ruffle strip in place.

Referring now more particularly to Figs. 5, 6 and 7, the main section 11 of the folding guide is formed of a strip of metal, which, at the entrance end, follows a reverse curve 20 from the top downward and thence extends upward and again down to form a narrow curved channel 21, the end of the latter receiving the edge of the main fabric *a*. The fabric being partly introduced, with the movable section 12 separated from the main section, said movable section is now moved up or closed and the fabric is forced by the vertically curved wall of section 12, into engagement with the reversely curved portion 20. As the discharge or exit end of the guide is approached, the curved walls gradually flatten until, as shown in Fig. 7, the double hem is formed and the "pocket" is held open to facilitate the introduction of the ruffle strip *e*. To the rear edge of the plate 10 is secured a bracket 30 carrying the stripper blade 31 of the ruffler. The ruffling blade acts in the usual manner and feeds the fabric forward, but, as before mentioned, the feed takes place in such a manner that the ruffle strip is directed under the inner needle only.

I claim—

- 40 1. A folder comprising equally spaced similarly shaped guiding walls, one of which is movable relative to the other to permit the insertion of the material between said walls, the receiving side at the entrance to said folder being substantially upright, and stops for limiting the movement of the movable wall toward the coöperating wall whereby said walls are spaced a predetermined distance relative to each other.
- 45 2. A folder comprising equally spaced similarly shaped guiding walls, one of which is movable relative to the other to permit the insertion of the material between

the walls, the receiving side at the entrance to said folder being substantially upright and the receiving side for the fabric at the delivery end thereof being substantially horizontal, said guiding walls at the lower portion thereof being formed with stops for spacing the walls of the folder so as to provide a free passage of the fabric.

3. A folding guide comprising a base, guiding means mounted on said base to fold the fabric back and forth upon itself, said guiding means including substantially parallel guiding walls one of which is movable relative to the other, said guiding means also having a guiding space for a second piece of fabric, which enters between the folds of the body fabric; substantially as described.

4. A folding guide comprising a base, guiding means mounted on said base to fold the fabric back and forth upon itself, said guiding means including similarly shaped guide walls, one of which is movable relative to the other to permit the insertion of the fabric between the guiding walls, said guiding means also having a guiding space for a second piece of fabric which enters between the folds of the body fabric, and coöperating stops for positioning the walls of the folder relative to each other so as to properly space the walls and provide a free passage for the fabric.

5. A folding guide comprising substantially parallel guiding walls which are spaced at the top to receive a body fabric, said guiding walls being bent so as to be substantially U-shaped in cross section at the delivery end with the lower portion of said guiding walls bent inward to fold in the lower edge of the fabric, said U-shaped space in one of the guiding walls being adapted to receive a second fabric whereby the edge of said second fabric may be stitched between the folded portions of the body fabric, one of said walls being movable relative to the other.

In testimony whereof I affix my signature, in presence of two witnesses.

EDWARD BURKE.
